UNITED STATES PATENT OFFICE.

GREGORY GERDOM, OF WATERVLIET, NEW YORK.

ENVELOP-MOISTENER.

1,244,975.

Specification of Letters Patent. Patented Oct. 30, 1917.

Application filed May 7, 1917. Serial No. 167,031.

To all whom it may concern:

Be it known that I, GREGORY GERDOM, a citizen of the United States, residing at Watervliet, in the county of Albany and State of New York, have invented certain new and useful Improvements in Envelop-Moisteners; and I do declare the following to be a full, clear, and exact description of the invention, such as will enable others skilled in the art to which it appertains to make and use the same.

My invention relates to moistening devices for moistening envelop flaps, stamps and the like and its primary object is to provide an improved form of moistener providing a novel construction and arrangement of parts which will be simple and cheap to manufacture and which will at the same time be durable and most efficient in operation.

A further object of my invention is to provide a moistener support which is so constructed that when the support is secured above a table it will hold the moistener in spaced relation from the table and will allow the moistener to be readily manipulated over the table when it is desired to use the same.

With these and other general objects in view which will appear from the description the invention resides in the novel construction, combination and arrangement of parts to be more fully hereinafter described and claimed when taken in connection with the accompanying drawings which form a part of this application.

In a copending application Serial No. 164731, I have described and generically claimed the construction and principles of operation of my improved moistener.

In the accompanying drawings:

Figure 1 is a side elevation of my improved moistener in retracted position;

Fig. 2 is a similar view showing the same extended;

Fig. 3 is a detail vertical section of the container;

Fig. 4 is a view of a modified form of container;

Figs. 5 and 6 are detail horizontal sectional views on the lines 5—5 of Fig. 2 and 6—6 of Fig. 3 respectively.

Briefly my invention comprises a fluid container provided with fluid distributing means thereon and mounted on a lazy tongs secured to a wall bracket so that it may be

easily manipulated when it is desired to use the same. The improved moistener in detail comprises a channel wall bracket 1 having a bottom 2 and laterally extending side flanges 3. The wall bracket is substantially rectangular in shape and is provided at its ends with apertures to receive therethrough screws or other fastening members for securing the bracket to a wall or desk or any suitable support as may be desired. The bracket is preferably vertically disposed and at spaced intervals on the bottom 2 is a pair of laterally extending lugs 4 apertured to receive therethrough a pivot pin 5 and mounted on the pivot pin and secured thereon between the lugs 4 are sleeves 6 having attached thereon the levers 7 of the lazy tongs 8.

A table or envelop holder T is suitably supported below the lazy tongs so that an envelop may be placed on the table and the moistener to be described, drawn out over the flap of the envelop pressed down and moved laterally thereon.

Owing to the fact that the lazy tongs are made of metal they have a certain flexibility. If no downward pressure is exerted the moistener will be held vertically spaced from the table but when a downward pressure is exerted the bottom of the moistener will come in contact with the table due to a certain vertical play allowed by the resiliency of the lazy tongs. This is an important feature of my invention as it allows the moistener to be positioned near the top of the table and prevents leakage which would occur if the moistener was positioned on top of the table.

At the opposite end the levers 7 of the lazy tongs are pivotally secured to attaching lugs 9 formed on a cylindrical fluid container casing 10 having a conically reduced lower end 11 and an open upper end adapted to be closed by a detachable cap 12 suitably secured thereto. Disposed in the conically reduced lower end 11 and projecting slightly therebeyond is a fluid spreader member 13 which may be of any approved form and which is so disposed as to be moved freely with respect to the walls of the casing or if preferable which may be secured thereto so as to distribute fluid on the article to be moistened when the same is passed thereover.

When the lazy tongs 8 is in retracted position the levers 7 comprising the tongs will be compressed between the channel of the

bracket 1 and the lugs 9 on the cylindrical walls of the fluid container casing 10 which will then assume its position substantially between the ends of the side flanges as illustrated in Fig. 1. As a means of manipulating the bracket and container casing I provide a handle member 14 which may be of any configuration preferred and which is integrally formed or rigidly secured to the 10 casing 10 diametrically opposite the attachings lugs 9 in this approved form of my invention.

Seated on the conically reduced walls 11 of the lower end of the casing is a valve 15 which is spaced inwardly a sufficient distance from the lower end of the casing as to provide a slight clearance for the spreader member 13 when the same is actuated. The valve is provided with a vertically extending 20 stem 16 projecting at its upper end beyond the top of the casing and slidably through the detachable cap member 12. At its upper end a handle member 17 is secured thereon to provide a means for opening and closing 25 the valve 15 as desired. Removably positioned within the casing is a pair of spiders 18 having radially extending arms 19 in slid- able engagement with the walls of the casing. These spiders are vertically spaced from one 30 another by a connecting tube 20 suitably threaded at either end to the spider members and adapted to act as a guide for the stem 16 and surrounding the same throughout the greater portion of its length. As a means 35 for normally holding the valve seated I provide a coil spring 21 having suitable connec- tions between the stem 16 and the detach- able cap 12 whereby to force the valve down- wardly upon its seat at all times.

40 In the operation of my improved moistener the handle member 14 is grasped to pull the container casing outwardly and extend the lazy tongs to bring the container in the position desired. Then a slight downward pres- 45 sure is exerted on the moistener and it is moved over to the flap of an envelop to op- erate the spreader member 13. The spreader member 13 may be a brush detachably se- cured in the lower end of the casing or a ball 50 positioned therein whereupon the same will be caused to deliver moisture to the surface of the flap or other article. If the spreader member comprises a ball it is merely neces- sary to exert a slight inward pressure or lift- 55 ing movement upon the ball whence the same will be caused to engage the valve 15 lifting it from its seat and delivering a portion of its contents on the spreader member. Upon the pressure being relieved the valve will 60 again be seated under the action of the spring 21 and the ball may be rotated by action of the flap of the envelop being passed there-

over so as to deliver the fluid upon all parts thereof after causing the valve to be lifted. When it is desired to use a brush as a 65 spreader member it is simply necessary to grasp the handle member 17 on the valve stem 16 and draw the same upwardly against the action of the spring 21 to lift the valve from its seat and deliver fluid to the brush. 70 The spring 21 will, as is obvious, return the valve to its seat in the upward pull and the handle 17 is released.

I do not confine myself to any specific ma- 75 terial used in the construction of this im- proved moistener as the container may be filled with any suitable fluid or disinfectant as may be desired, but I find it preferable to construct the container casing in a bracket of a light metal which will insure a strong 80 and durable device.

In Fig. 4 of the drawing I have illustrated a modified form of my invention in which the spreader member comprises a brush 13' 85 mounted in the lower end of the casing in place of the ball 13. All other parts of the device are identical in every respect with the form hereinbefore described and in the description already given the function and operation of the brush member 13' has been 90 definitely set forth and therefore it will not be necessary to elaborate on the same.

While I have described and illustrated in the accompanying drawings certain ap- 95 proved forms of my invention and certain details as to the construction thereof, I de- 100 scribe to be understood that I do not limit myself to any specific construction, combination and arrangement but that any changes may be made in the minor details of its construc- 105 tion and that any materials desired may be used as will fall within the scope of the in- vention as claimed.

What I claim is:

The combination with a moistener of a 105 pair of lazy tongs having means at one end to hold the moistener, the other end of said tongs being pivotally mounted above a table in such a manner that the moistener will be held vertically spaced from said table, said table forming means to support the envelop 110 to be moistened and said lazy tongs being adapted to resiliently yield when downward pressure is exerted on the moistener so that said moistener will contact with the envelop 115 on the table.

In testimony whereof I have hereunto set my hand in the presence of two subscribing witnesses.

GREGORY GERDOM.
